(57) **CLAIM**

The ornamental design for a pop filter, as shown and described.

DESCRIPTION

FIG. 1 is a rear top perspective view of a pop filter showing the new design;

FIG. 2 is a front top perspective view of the pop filter of FIG. 1;

FIG. 3 is a rear bottom perspective view of the pop filter of FIG. 1;

FIG. 4 is a front bottom perspective view of the pop filter of FIG. 1;

FIG. 5 is a right side view of the pop filter of FIG. 1;

FIG. 6 is a rear view of the pop filter of FIG. 1;

FIG. 7 is a left side view of the pop filter of FIG. 1;

FIG. 8 is a front view of the pop filter of FIG. 1;

FIG. 9 is a top view of the pop filter of FIG. 1; and,

FIG. 10 is a bottom view of the pop filter of FIG. 1.

The difference in shading in the figures indicates a contrast of appearance and does not depict any particular color, texture, or material.

The broken lines shown in the drawings are for the purpose of illustrating portions of the pop filter and form no part of the claimed design.
